Des. 187,661
Patented Apr. 12, 1960

187,661

MARBLE GUN

Bernard A. McDermott, Akron, Ohio, assignor to The Cardinal Rubber Co., Barberton, Ohio, a corporation of Ohio

Application October 16, 1958, Serial No. 53,003

Term of patent 14 years

(Cl. D34—15)

FIG. 3

Fig. 1 is a top plan view of a marble gun of my new design;

Fig. 2 is a side elevation of the gun; and
Fig. 3 is a front view of the gun.

I claim:

The ornamental design for a marble gun, as shown.
